UNITED STATES PATENT OFFICE.

WILLIAM R. DUTEMPLE, OF PROVIDENCE, RHODE ISLAND.

DESIGN FOR AN ADVERTISING-CARD FOR SCARF-PINS.

SPECIFICATION forming part of Design No. 16,787, dated July 13, 1886.

Application filed March 24, 1886. Serial No. 198,425. Term of patent 14 years.

To all whom it may concern:

Be it known that I, WILLIAM R. DUTEMPLE, a citizen of the United States, residing at Providence, in the county of Providence and State 5 of Rhode Island, have invented and produced a new and original Design for Scarf-Pin Pads; and I do hereby declare the following to be a full, clear, and exact description of the invention, reference being had to the accompanying 10 drawing, and to letters or figures of reference marked thereon, which form a part of this specification.

This invention relates especially to a design 15 for an advertising-card for scarf-pins; and it consists of a pad or base on which is represented a human hand (palm in front) having the fingers partially bent or closed, and the thumb thereof represented as extending across the palm.

20 Another element of the design consists in the representation of a series of loops or holders adjacent to the said fingers, the whole being an exhibition or display card for scarf-pins, &c.

25 In the accompanying drawing is represented a practically full-size view of my improved design, the elements composing it being as follows:

20 C is the hand or holder, representing and having the configuration of a partially-closed hand, the fingers *c* being extended and slight-

ly bent and touching each other, the thumb *d* extending in front of and across the palm or hollow of the hand *C*.

B, another element of the design, represents 35 a card or base on which the loops or holders *b* and the said hand *C* are represented, the whole showing a person's hand retaining a number of radially-arranged pins having the points thereof concealed by the extended thumb. 40

Having thus described my invention, what I claim as my design, and am desirous of securing by United States Letters Patent, is—

1. The design for an advertising card or pad, consisting, essentially, of the card or base *B*, 45 the open hand *C*, and loops *b*, substantially as described in the specification and shown in the accompanying drawing.

2. The design for an advertising-card for scarf-pins, having thereon the representation 50 of a partially-open hand, with the extended thumb *d* and the loops or holders *b* adjacent to the fingers *c*, substantially as hereinbefore described, and shown in the accompanying drawing.

55 In testimony whereof I have affixed my signature in presence of two witnesses.

WM. R. DUTEMPLE.
